UNITED STATES PATENT OFFICE.

SPENCER OTIS, OF CHICAGO, ILLINOIS, AND LESLIE B. GRAHAM, OF EAST CHICAGO, INDIANA.

HEATER FOR OIL-PIPE LINES.

Application filed June 10, 1922. Serial No. 567,321.

To all whom it may concern:

Be it known that we, SPENCER OTIS and LESLIE B. GRAHAM, citizens of the United States, residing, respectively, at Chicago, in the county of Cook and State of Illinois, and at East Chicago, in the county of Lake and State of Indiana, have jointly invented certain new and useful Improvements in Heaters for Oil-Pipe Lines, of which the following is a specification.

This invention relates to heaters for oil pipe lines and has for its object to provide a heating pipe within an oil conduit, and automatic means for supplying a heating medium thereto commensurately with the absorption of heat by the oil flow in the line.

It has heretofore been proposed to circulate steam through a pipe enclosed within an oil pipe line for the purpose of keeping up the temperature of the oil to a degree at which it is sufficiently fluid for pumping, but, as heretofore arranged, such systems have been uneconomical in that they involve a constant discharge of the heating medium.

The present invention proceeds upon the principle of supplying the heating medium to the pipe within the oil pipe line under continuing pressure, so that it will be ready at all times to advance to the heating pipe, and so throttling the outlet of said heating pipe or a return pipe leading therefrom, and so controlling the throttle by the temperature of the returning heating medium that the heating medium will remain in the heating pipe until, by transfer of its heat to the oil, its temperature falls to a predetermined degree, when the throttle will be automatically opened or increased in opening sufficiently to bring a new charge of heating

medium into the heating pipe; or, with a proper balance or adjustment of the system, the throttle opening will be maintained at such a degree that the flow of heating medium through the heating pipe will be more or less constant and at such a rate as will permit it to give off its heat during its progress through the enclosed portion of the heating pipe. The invention also contemplates, in its preferred embodiment, the employment of water as the heating vehicle and the use of means whereby the water will be automatically returned to the boiler or source of heat periodically, and as it accumulates in volume sufficient to initiate the action of a pump relied upon for its return.

In the accompanying drawing—

Figure 1 is a schematic view of an oil pipe line, together with the heating system of the present invention.

Figure 2 is a section on the line 2^x—2^x 60 of Figure 1 on an enlarged scale.

Figure 3 is a detail view of the thermostatically controlled throttle, also on an enlarged scale.

Figure 4 is a detail in side elevation of 65 the means for automatically returning water from the tank to the boiler.

A represents an oil pipe line, such, for instance, as one leading to a pump house B and from said house to a tank C. Inasmuch 70 as crude oil, particularly in cold weather, becomes sluggish and difficult to pump, it is desirable to maintain within the pipe line A means for keeping up the temperature of the oil flowing therethrough. To that end 75 the present invention introduces a circulatory heating pipe 1 which may have its return leg 1^a, as well as its supply leg, enclosed within the pipe; and this pipe is supplied from a boiler 2 of any suitable construction, which communicates therewith through a feed pipe 3 preferably provided with a pressure reducing valve 4. In order 80 economically to supply water to the heating pipe 1, the water is returned to the boiler 2 after its heat is given off, but return flow and, consequently, outflow of the water is automatically governed by the giving up of the heat to the oil in the pipe line, and to accomplish this the return leg 1^a of the heating pipe is connected with a return pipe 5 that leads to a tank 6, whence the water is forced by a pump 7 back into the boiler 2. Located between the return leg 1^a and the return pipe 5 is a throttle valve 8, which opens 85 automatically only when the temperature of returning water falls to such a degree as to indicate that additional hot water is required in the pipe 1, said valve 8 being under control of a thermostat 9 located in a governor pipe 10 lying between return leg 1^a and return pipe 5.

In order that the thermostat 9 may truly reflect the temperature of water in the heating pipe 1, 1^a, a slight circulation 100 past the throttle valve 8 will be maintained at all times by so adjusting the valve that it will never be completely closed at any temperature under which the system is intended to operate, and an increased opening 110

will occur and permit an inflow of hot water to replenish lost heat, theoretically, whenever the temperature of water in the restricted flow becomes lower than the predetermined degree. In practice the thermostat will act to hold the valve in an intermediate position and permit a more or less constant flow of water commensurate with the fall in temperature from the inlet to the outlet end of the heating pipe, subject, of course, to such fluctuations or variations in the speed of flow as may be induced by variations in the heat absorption by the surrounding oil.

15 Preferably the pump 7 would not act constantly in returning the water from tank 6 to boiler 2, but periodically and only as the water in the tank accumulates to a predetermined level; and to this end a fluid-holding counterbalance 12, communicating through a flexible pipe 13 with the tank 6 at a level upon the attainment of which it is desired to have the pump operate, is suspended through a connector 14 from the end 20 of a weighted lever 15, which controls the valve 16 in steam pipe 17 connecting the engine with the boiler, so that whenever the water reaches the predetermined level in the tank 6 the pump will operate to draw water 25 through pipe 18 from the tank and deliver it through pipe 19 to the boiler, until the counterbalance 12 is emptied again, when the now relieved weighted lever 15 will act to close the valve 16 and arrest the action 30 of the pump.

As suggested in Figure 2, the outflow leg 1 and return leg 1^a of the heating pipe may be effectively mounted in the oil line pipe A by means of stanchions 20.

40 Preferably the heating plant will be located at an intermediate point along the pipe line and will have its water supply and return connections duplicated in order to reduce the length of circulation and keep up 45 the efficiency of the heating operation. To that end supply pipe 3 is connected by branch pipes 21 with duplicate outflow and return legs 1, 1^a of the heating pipe lying on opposite sides of the heating installation, 50 and, similarly, the return flow pipe 5 will have its connections 10 and 11 duplicated and connected therewith through the manifold pipe 22. The heating plant is advantageously located at or adjacent the pumping station B, and the branches of the heating pipes and connections are distributed 55 on opposite sides of said station.

We claim:

1. An oil pipe line heating system, comprising heating pipes within the pipe line,

a source of heating medium connected with said heating pipes, a return flow connection for said heating medium, and means controlling the passage of heating medium through said return flow connection, which is subject to the temperature of the returning medium. 65

2. In a heating system for oil pipe lines, a heating pipe enclosed in the line, a source of heating medium connected with said pipe, a return passage also connected with said pipe, a thermostat in said return passage, and a valve in said return passage controlling the flow therethrough and which is, in turn, controlled by said thermostat. 70 75

3. In a heating system for oil pipe lines, a heating pipe enclosed in the pipe line subdivided into a plurality of units, a common source of heating medium connected with all of said heating units, and individual return flow connections for the respective heating units, having independent means for controlling the flow therethrough, which means are subject to the temperature effects 80 of the heating medium. 85

4. A heating system for oil pipe lines and the like, said system comprising an oil container, a heating pipe within said container having charging and discharging connections, means for supplying a hot liquid heating medium to the charging connection, means for causing said heating medium to flow through said heating pipe and connections, in volume proportional to resistance to said flow, means for varying said resistance located in the discharge connection, and a thermostat responsive to heat effects of oil heating liquid which flows through the discharge connection; said thermostat being connected with said resistance varying 100 means and reducing resistance to flow as the temperature of the discharged heating liquid falls, and increasing resistance to such flow as the temperature of discharged heating fluid rises. 105

5. In a heating system for oil pipe lines, a heating pipe enclosed in said line, a boiler, a supply pipe leading from said boiler to said heating pipe, a return flow pipe leading from said heating pipe, a tank receiving heating medium from said return flow pipe, a pump returning heating medium from said tank to said boiler, and means controlled by the accumulation of heating medium in said tank, which, in turn, controls 110 the operation of said pump. 115

Signed at Chicago, Illinois, this 7th day of June, 1922.

SPENCER OTIS.
LESLIE B. GRAHAM.
